BRASSIÈRE

Leonard S. Florsheim, Jr., Chicago, Ill., assignor
to Kabo, Inc., a corporation of Illinois

Application March 20, 1947, Serial No. 736,066

2 Claims. (Cl. 2—42)

1

This invention relates to brassières and to foundation garments having breast supporting pockets, and particularly to means in such articles for reinforcing and stiffening the lower portion of the breast supporting pockets without destroying the flexibility necessary to permit the pocket to conform to the contour of the wearer's bust.

The brassière or foundation garments generally have their breast supporting pockets so flexible that they do not mold the wearer's bust into the attractive contour desirable in this type of apparel, or so stiff that they do not give a natural looking appearance when worn. Other disadvantages of some brassières of the prior art are that the material used to provide support for the breasts is relatively heavy and tends to sag in time, and additionally, due to the use of rubber in making the support, seals a substantial portion of the bust in an air-tight enclosure that induces perspiration. The provision of an absorbent material, such as flannel, in such brassières is not an adequate solution of the problem of perspiration because the flannel can absorb only the moisture and not the concomitant odor.

In accordance with the present invention the breast supporting pockets of the brassière or foundation garment are made with a relatively light weight, plastic-coated fabric that is stiff enough to provide adequate support for the wearer's breasts, and yet is flexible enough to cause the pockets to be molded to the natural contours of the breasts.

The upper portion of the breast supporting pocket, where no support is required, is made of a single thickness of satin or some similar material that presents a suitable appearance. The lower portions of the pockets which actually support the breasts are made of two layers of fabric. The outermost of such layers may be of the same material as the upper portion or similar material so the front of the brassière or garment will have a pleasing appearance. The inner breast supporting layer of each pocket has a thin film of resinous material or similar plastic material applied to its inner surface, and this layer is secured around the marginal edges to the outer layer so that, in effect, the inner layer is separate from and largely independent of the outer layer. The plastic coating does not permeate the fabric and therefore does not come into contact with the wearer's skin.

In a modified form of the invention the breast supporting fabric is made to "breathe" (capable of readily venting moisture) by the provision

5 of perforations. It will be understood that when the outer layer is of a reticulated material or an imperforate material provided with perforations, the perforations are preferably very minute, so as not to detract from the appearance of the brassière.

The structure by which the various results are attained will be described in connection with the accompanying drawings, in which:

10 Figure 1 is a front perspective view of a brassière embodying the invention;

Fig. 2 is a cross sectional view taken along the line 2—2 of Fig. 1;

15 Fig. 3 is a magnified cross sectional view taken along the line 3—3 of Fig. 2;

Fig. 4 is a fragmentary rear elevational view of a modified form of breast-supporting pocket embodying the present invention, showing the face of the perforated, plastic-coated, stiffening 20 fabric which is brought in contact with the wearer; and

Fig. 5 is a magnified cross sectional view taken along the line 5—5 of Fig. 4.

In the drawings the reference numerals 2 and 25 3 indicate a pair of breast supporting pockets sewed together at the top portions of their meeting lateral edges, as indicated at 4. The lower portions of these lateral edges are spaced apart and joined by a gusset 5 of suitable elastic fabric.

30 The outer lateral edges of the breast pockets have band portions 6 and 7 secured thereto for encompassing the back of the wearer. Band portion 7 is provided with an elastic extension 8 having eyes 9 secured thereto. Hooks 10 secured 35 to the edge of band portion 6 are adapted to engage eyes 9 to fasten the brassière around the bust of the wearer. Conventional shoulder straps 11 and 12 are secured to the upper edges of the brassière.

40 The breast supporting pockets are duplicates, so only one will be described. The upper portion 13 of the pocket is formed of any suitable knitted or woven, textile fabric such as satin, for example. The front or outer side 14 of the lower portion of the pocket may be made of the same material as upper portion 13 or of other textile material of suitable pleasing appearance. The upper and lower portions of the breast supporting pocket are sewed or otherwise joined together

45 and either subsequently or prior to this operation the lower portion has secured to its inner side a textile fabric 15 coated on its inner surface only with a film 16 of resinous or similar plastic material.

50 The plastic material serves to stiffen the fabric

somewhat and thereby partially eliminates its flexibility. It is accordingly applied in a film of such thickness as to impart to the fabric the desired stiffness and flexibility. This coated fabric is secured around its marginal edges to lower portion 14, with the coating 16 opposed to portion 14 but not adhered thereto. In effect, therefore, the coated stiffening fabric is independent of portion 14, since the latter does not augment the stiffening characteristics of the coated layer. Since film 16 is positioned entirely on the inner surface of fabric 15 and does not permeate the fabric it cannot come into contact with the wearer's skin.

The lower portion of the brassière, comprising the outer layer of satin or similar fabric, and the inner layer of fabric coated only on its inner surface with resin, is firm enough to furnish adequate support for a woman's breast and flexible enough to conform to its contour.

The plastic film may be applied in the form of a thin coating on the surface of the fabric in accordance with conventional procedures, as by roller coating from a tank containing the coating in molten liquid form or in solution form, or by spraying, or otherwise, as desired. The film may be formed of a thermoplastic resinous material such as polyvinyl acetate, polyvinyl chloride, polyvinyl butyral, polyvinyl alcohol, copolymers of polyvinyl chloride and polyvinyl acetate, polyvinylidene chloride, polyethylene, methyl methacrylate, polystyrene, etc. The copolymer of polyvinyl chloride and polyvinyl acetate is a preferred material. Or the film may be formed of a cellulose derivative such as, for example, cellulose acetate, cellulose acetate-butyrate, cellulose acetate-propionate, ethyl cellulose, methyl cellulose, nylon or similar synthetic long chain linear polyamides, etc. A suitable cellulose derivative plastic composition is described in Patent No. 2,128,600.

The film may also be formed from liquid, polyfunctional materials which are capable of polymerizing to an infusible and insoluble resinous state such as diallyl phthalate, diallyl maleate, diallyl fumarate and unsaturated alkyds such as ethylene glycol maleate, ethylene glycol itaconate, ethylene glycol fumarate and like polymerizable compounds having a plurality of unconjugated carbon to carbon double bonds, either alone or in admixture with monofunctional materials such as styrene, vinyl acetate, methyl methacrylate, polyvinyl alcohol and the like. As is known, such polymerizable materials may be cured to the final, insoluble state by heat and/or light, preferably in the presence of polymerization catalysts such as benzoyl peroxide, lauroyl peroxide, methyl ethyl ketone peroxide and the like.

The film may also be formed from other resinous materials which are capable of being converted to the infusible and insoluble state such as furfuryl alcohol, condensation products of furfuryl alcohol, an aminotriazene such as melamine, and an aldehyde such as formaldehyde, paraformaldehyde, furfural, acetaldehyde, benzaldehyde, and the like, or from equivalent thermosetting resinous materials. Where the film is to be formed from furfuryl alcohol alone the furfuryl alcohol should be preliminarily converted to a thickened state as by condensation of the furfuryl alcohol with the aid of an acid catalyst or by heat, to prevent undue penetration of the resin precursor into the fabric.

The same procedure should be employed where the resin precursor is a polymerizable monofunc-

tional monomer such as styrene or vinyl chloride or a polyfunctional monomer such as diallyl phthalate or diallyl maleate. These polymerizable materials can be preliminarily converted to a thickened adhesive state as by heating them in the presence of a polymerization catalyst such as benzoyl peroxide, and then applied as a surface coating on the fabric. The coating can then be cured to the final state by heat and/or light, in accordance with conventional procedures.

In the modified embodiment of the invention illustrated in Figs. 4 and 5, the general structure of the breast supporting pocket is the same as hereinabove described. The only difference between the two embodiments is that the fabrics 15' and 14' are provided with perforations 17 and 18, respectively, to facilitate breathing of the fabrics. The perforations in fabric 14' are preferably minute so as not to detract from the appearance of the brassière or foundation garment. Coated fabric 15' is preferably perforated to a greater extent than fabric 14'. As is apparent from Fig. 5, the perforations in fabric 15' continue on through the plastic film attached thereto.

Although two preferred embodiments of the invention have been described in considerable detail, it will be understood that the description thereof is intended to be illustrative, rather than restrictive, as many details may be modified or changed without departing from the spirit or scope of the invention. Accordingly, I do not desire to be restricted to the exact structures described, except as limited by the appended claims.

I claim:

1. A breast supporting garment comprising a pair of substantially similar breast receiving pockets and means for supporting the same in position upon the body of the person wearing the same, each of said breast receiving pockets having an upper portion of flexible fabric and a lower portion formed of two layers of flexible fabric, an outer layer and an inner layer, said inner layer being of smaller dimensions than said outer layer and being marginally secured to the said outer layer but otherwise separated therefrom, said inner layer extending over substantially the entire area of the said outer layer except for the nipple area and the area immediately adjacent the bottom of said outer layer, and said inner layer having on the inner surface only thereof a flexible plastic coating in the form of a film integrally bonded to the said inner surface, the said plastic film imparting to the said inner layer a limited stiffness which enables the said plastic-coated inner layer to support the breast and yet permits the same to conform to the natural contour of the breast.

2. A breast supporting garment comprising a pair of substantially similar breast receiving pockets and means for supporting the same in position upon the body of the person wearing the same, each of said breast receiving pockets having an upper portion of flexible fabric and a lower portion formed of two layers of flexible fabric, an outer layer and an inner layer, said inner layer being of smaller dimensions than said outer layer and being marginally secured to the said outer layer but otherwise separated therefrom, said inner layer extending over substantially the entire area of the said outer layer except for the nipple area and the area immediately adjacent the bottom of said outer layer, and said inner layer having on the inner surface only thereof a flexible plastic coating in the form of a film

integrally bonded to the said inner surface, the said plastic film imparting to the said inner layer a limited stiffness which enables the said plastic-coated inner layer to support the breast and yet permits the same to conform to the natural contour of the breast, and a plurality of perforations in the said outer layer and the said plastic-coated layer of the lower portions of said breast receiving pockets to permit said layers of fabric to "breathe."
